United States Patent Office.

HENRY H. ELWELL, OF SOUTH NORWALK, CONNECTICUT.

Design No. 4,432, dated October 25, 1870.

DESIGN FOR A KEEPER FOR DOOR-LOCKS.

The Schedule referred to in these Letters Patent and making part of the same.

To all whom it may concern:

Be it known that I, HENRY H. ELWELL, of South Norwalk, in the county of Fairfield and State of Connecticut, have invented a new Design for Keeper for Door-Locks; and I do hereby declare the following, when taken in connection with the accompanying drawing and the letters of reference marked thereon, to be a full, clear, and exact description of the same, and which said drawing constitutes part of this specification, and represents a front view.

This invention relates to a design for the ornamentation of the keeper of door-locks, and consists in a matted surface with raised figures of a peculiar character, as shown in the drawing.

A is the lock-bolt opening.
B the latch-bolt opening.

The lock-bolt opening is surrounded by a tracery extending to the edges of the keeper, with corresponding tracery from the upper and lower ends of the latch-bolt opening, and at each end of the keeper, all as fully shown in the accompanying drawing.

I claim as my invention—

The design for keeper for door-locks, as shown in the drawing, and described.

H. H. ELWELL.
